CLAIM

The ornamental design for a display screen or portion thereof with graphical user interface, as shown and described.

DESCRIPTION

FIG. 1 is a front view of a first embodiment of a display screen or portion thereof with graphical user interface;

FIG. 2 shows the design of FIG. 1 in the context of a different broken line environment;

FIG. 3 shows the design of FIG. 1 in the context of a different broken line environment;

FIG. 4 is a front view of a second embodiment of a display screen or portion thereof with graphical user interface; FIG. 5 is a front view of a third embodiment of a display

FIG. 5 is a front view of a third embodiment of a display screen or portion thereof with graphical user interface; FIG. 6 shows the design of FIG. 4 in the context of a

FIG. 6 shows the design of FIG. 4 in the context of a different broken line environment;

FIG. 7 shows the design of FIG. 1 in the context of a different broken line environment;

FIG. 9 shows the design of FIG. 1 in the context of a

FIG. 10 shows the design of FIG. 4 in the context of a

different broken line environment. The outermost broken lines illustrate a display screen or window frame for a computer terminal. The innermost broken lines are the 11 lines of the 11-line 11-line. The

portion thereof and form no part of the claimed design. The remaining broken lines illustrate portions of the graphical user interface that form no part of the claimed design.

user interface that form no part of the claimed design.
